UNITED STATES PATENT OFFICE.

FRANK TWYMAN, OF LONDON, ENGLAND, AND HAROLD WORKMAN, OF GLASGOW,
SCOTLAND.

PRODUCTION OF COLOR CINEMATOGRAPHIC BANDS AND MEANS THEREFOR.

1,312,088.

Specification of Letters Patent.

Patented Aug. 5, 1919.

Application filed November 21, 1916. Serial No. 132,591.

To all whom it may concern:

Be it known that we, FRANK TWYMAN and HAROLD WORKMAN, subjects of His Majesty King George V of the United Kingdom of Great Britain and Ireland and of the British Dominions beyond the Sea and Emperor of India, residing, respectively, at London, England, and Glasgow, Scotland, have invented certain new and useful Improvements in the Production of Color Cinematographic Bands and Means Therefor, of which the following is a specification.

The present invention relates to color record cinematographic bands and to means for producing them, these means appertaining to cinematographic cameras in which successive groups of two or three separate color record images of the same size or substantially the same size are simultaneously taken from the same point or aspect of view, by two or three lenses before which lenses is a bifurcating or trifurcating prism system for dividing the beam so as to form the two or three images in the same plane.

The invention is hereinafter more particularly described with reference to cinematographic cameras of the hereinabove described kind in which a branch is separated from the entering beam of light, by reflection in a partially transmitting and partially reflecting compound prism block (hereinafter called "compound prism block"), the direct beam passing through one objective (hereinafter called "direct lens"), while the branch beam reflected in the block is again reflected by a reflecting prism (hereinafter called "reflecting prism") fitted at the side of the compound prism block so that the axes of the direct beam and the branch beam are brought into parallelism and the branch beam traverses a second objective (hereinafter called "side lens"). Such a device is used in association with color screens appropriate to the two color system and the device should produce two sharply focused images in the same plane, and of substantially the same size for objects within the range of distance through which it is desired to use the taking system, (*vide*, English Patents Nos. 16810 of 1915 and 16811 of 1915).

Similarly two branches may be separated from the entering beam of light by provid-

ing a prism system having two partially reflecting and partially transmitting surfaces, 55 and two reflecting prisms, whereby the direct beam passes through a medial lens and the branch beams traverse second and third lenses arranged on either side of such medial lens, these side lenses being disposed so as 60 to bring their axes parallel with the axis of the medial lens, and the prism system being arranged so as to bring the axis of the direct beam and the axes of the branch beams into parallelism. 65

The foregoing are to be taken only as examples of optical systems for obtaining for the purposes of the present invention equality of size of images sharply focused on the same plane, and taken from the same 70 point or aspect or view.

When from negative cinematographic film bearing successive groups of separate color record images produced by taking systems of the class described, positive film is printed 75 for the production of cinematographic effects in color by simultaneously projecting with the aid of color filters the resulting positive color record images in successive groups by a two or three lens projector, there must be 80 such adjustment of the projection lenses in projecting such positive film, as will secure effective superimposition of the images of each and every heliochromic group on the screen. 85

As any incorrect superimposition of the color record images on the screen which may arise during the course of an exhibition can only be detected after the fault has occurred and is dependent for its correction upon adjustments made by the operator and as the requisite adjustments of the projection lenses to effect the correction takes some time and must be made without interrupting the continuity of the exhibition, any such defects in superimposition militate seriously against the even and successful course of the exhibition. Owing to the mechanical impracticability of making all similar taking systems of the class described true to standard to the very high degree of accuracy necessary, such defects in projection must ordinarily appear in most if not all cases where from negative films taken through two or more similar taking systems or units of the 100 class described, separate lengths of positive 105

film are made and joined up, for projection, in one continuous band or reel, and separate adjustment of the projection lenses will require to be made after most if not after all 5 film joins or film changes to obtain correct superimposition of the color record images.

The objects of the present invention are to provide means by which the above mentioned defects may be overcome or rendered negligible, and to provide new and improved arrangements of mounting the optical parts of 10 such taking systems.

In this connection the following requirements should be fulfilled to enable really 15 good films to be produced by cameras provided with taking systems of the class described.

Firstly the separate color record images 20 of each successive group should be sharply focused on one plane and should be of the same size or substantially the same size for objects within the range of distance through which it is intended to use the system, thereby securing images that can be effectively 25 superimposed upon the screen; secondly the negative images forming each group of color records should be set, each in an exact selected standard position in relation to each other and as a group to the course of 30 the film so that lengths of positive film printed from negative films which have been produced by two or more similar taking systems or units of the class described in the camera or cameras to which they have been 35 adapted can be joined up and projected one after the other in a suitable projector fitted with two or three lenses and color filters, without it being necessary to readjust the projecting lenses when changing from any 40 one film to any other of the same standard grouping of images; thirdly the removable front or panel of the camera on which the taking system is mounted should be under such registering control that when replaced 45 after removal for any purpose it can only occupy one definite position relative to the course in which the film travels when passing the gates or apertures through which the separate color images of each group are 50 taken.

The fulfilling of the foregoing requirements is necessary for the purpose of the present invention but other requirements which it is expedient also to fill as conducting to a higher attainment of the end or aim 55 of the present invention comprise mounting all parts of the taking system in a dust tight casing so that only the face of the front prism by which the light enters the 60 system and the rear faces of the lenses or the rear face of one of the lenses and the rear faces of a correcting block behind the other lens or each of the other lenses require occasional cleaning; and, further, the 65 diaphragms of the lenses should be made ad-

justable from the outside of such casing so that it is unnecessary to open it when adjusting the diaphragms.

To the foregoing end the present invention comprises an optical system of the kind 70 described located by steady pins or otherwise so that it can only occupy one definite position relative to the course in which the film travels, and provided with adjustments and clamping devices by which the lenses 75 can be brought into position and locked in position so that the separate color record images of each group are set, each in an exact selected standard position, in relation to each other and as a group to the 80 course of the film, thereby insuring effective superimposition on the projecting screen of the separate record color images of any film produced by any similar taking system so adjusted without it being necessary to re-adjust the projecting lenses when changing from any one piece of film taken by one such system to any other piece of film taken by any other such system.

Examples of adjustments for the lenses or 90 objectives which will serve in relation to the essential or main requirements of the present invention are as follows:—

Referring first to a two color cinematographic camera of the kind described and 95 to the diagrams figured 1 to 3 of the appended drawings, each lens (Figure 1) may be provided with a mechanical adjustment by one of which one lens can be adjusted vertically upward or downward and by the 100 other of which the other lens can be adjusted laterally across the front of the camera.

Or, as depicted by Fig. 2 one lens only 105 may be provided with both such mechanical adjustments, the other lens being fixed.

Or, as according to Fig. 3, one lens may be provided with a mechanical adjustment by which it can be adjusted for separation in relation to the other lens, and both lenses 110 may be conjoined to rotate as a whole about an axis disposed parallel to the lens-axes and lying in the plane of such lens-axes equi-distant from each.

Alternatively in any of the examples hereinabove given each lens may be provided with both adjustments. Further in the arrangement figured by Diagram 3, the prism system may be combined to rotate as a 115 whole with the lenses.

Referring to a three color camera of the kind described, and to the diagrams figured 4 to 6 of the appended drawings one lens (Fig. 4), (preferably the medial lens) is fixed and each of the side lenses may be 125 provided with mechanical adjustments, by which such lenses can be adjusted both vertically upward and downward, also laterally across the front of the camera.

Or, as depicted by Fig. 5, each of two of 130

the lenses (preferably the side lenses) may be provided with a mechanical adjustment by which it can be adjusted for separation in relation to its companion lenses, and the 5 remaining lens may be provided with an adjustment by which it can be adjusted in a direction at right angles to the direction of the before mentioned adjustment of each of the two lenses, all the lenses being so conjoined to rotate as a whole about an axis 10 coincident with the axis of the medial lens.

Or, according to Fig. 6, one lens (preferably the medial lens) is fixed and each of the two other lenses may be provided with a 15 mechanical adjustment by which it can be adjusted for separation in relation to its companion lenses, there being a further adjustment to one of the two other lenses by which it can be adjusted in a direction at 20 right angles to the direction of its other adjustment, and all the lenses being conjoined to rotate as a whole similarly to Fig. 5.

The above described mechanical adjustments may conveniently be of the screw or 25 cam type:

With any optical system of the kind described having means for bringing it to definite position as hereinabove defined and fitted with adjustments of the kind and for 30 the purposes hereinabove defined, the end or aim of the present invention can be well realized by proceeding in the following way:—

A camera of the class described has its 35 optical system located by two steady pins or like devices so that it can only occupy one definite position relative to the course in which the film travels, and the lenses by their adjustments are brought into position and 40 locked in position so that the similar and equal sized separate color record images of each group are set, each in an exact selected standard position to each other and as a group to the course of the film.

45 Now with the aid of resulting positive pictures from this camera, the projection lenses or objectives of a projector are adjusted by similar adjustments to a setting by which the separate color record images 50 of any group or any positive film printed from any negative film taken by said camera will effectively superimpose on the screen when projected by the said projector. This adjustment having been made, the projection 55 lenses are locked in this standard position. Thus a standard projector is established to which further optical systems under registering control for position as defined can be referred for the purposes of 60 adjusting these to conform to the standard projector.

For this purpose, another optical system in its mount is fitted to the same camera, or to another camera of the same type to 65 which it is adapted and by adjustments

made as for example under the guidance derived from observation of the projection effects produced by the standard projector of resulting positive pictures from this other taking system, the lenses of such other taking system are adjusted to a setting which is in accord with the standard projector and by which the separate color record images of any group of any resulting positive film from this other taking system will effectively superimpose on the screen when projected by the standard projector. This adjustment having been made, the lenses of this other optical system are then locked in the standard position. 70 75

In this way any number of optical systems fitted to the camera or cameras to which they have been adapted may be adjusted to conform to the standard projector for the production of cinematograph film 80 85 which fill the hereinabove defined essential requirements of the present invention, the lenses being locked when this end or aim is realized.

With the aid of the accompanying drawings we will now describe convenient and advantageous means conducive to carrying the present invention into practice particularly with reference to producing cinematograph bands wherein the color record 90 elements of the heliochromic groups are arranged side by side at the same level or substantially the same level on a broad band, and in which the taking system chosen for illustration is of the kind for two color 95 heliochromy forming the subject matter of British Patent No. 16811/1915.

In the drawings:—

Figs. 1 to 6 are diagrams illustrating 100 105 adjustments of the lenses hereinbefore referred to.

Fig. 7 is a plan view partly in section of a taking system according to this invention, the system being illustrated as applied to a removable front or panel of a cinematograph camera. 110

Fig. 7^a is a detail view hereinafter referred to.

Fig. 8 is a side elevation partly in section.

Fig. 9 is a front view with the cover and 115 prism mounts removed, the upper half of the circular portion, as shown in unbroken line being taken on a section at or in the plane of the flange of the lens e, Fig. 7.

Figs. 10 and 11 are details of the helical 120 focusing mount hereinafter described, Fig. 11 being a section on line x, x of Fig. 10.

Fig. 12 is a detail view of the means of positively adjusting and locking the lens mount, and,

Fig. 13 illustrates another method of constructing the dust tight chamber for the prism system before the lenses.

In the depicted arrangement as shown by Figs. 7, 8, 9 (dotted outline) and 13, a shows 130

a removable front or panel in which are two steady-pin holes, *b b*, Fig. 9 to secure exact positioning. This removable panel carries the optical system and the two registering holes *b b* engage over two steady pins on the fixed front of the cinematographic camera and bring the removable front or panel *a*, Fig. 9 to a definite position as hereinbefore laid down, the seating or main front for this purpose being rigidly connected to the gate film track and general mechanism. Thus the removable front bearing the optical system for projection can be instantaneously set into absolute adjustment 15 or relation to the film carrying mechanism.

The combined lens and prism system comprising the compound prism block *c*, reflecting prism *d*, direct lens *e*, side lens *f* and correcting block *g*, is combined unitwise 20 with a mount fitted with a screw adjustment by which all the parts may be moved together in focusing. The mount depicted is of the so called helical type, *i. e.*, the mount is a sliding barrel which is constrained in movement in its guide by pins co-acting with helical slots arranged so as to impart to and fro longitudinal motion to the barrel. As figured or shown, *h h*, Figs. 7 and 8, is a flanged tubular mount, or fixed 25 sleeve integral with or fast to the removable panel or front *a*, Figs. 7 and 8. The sliding barrel mount *k*, Figs. 7 and 8, carries the whole optical system for projection and the barrel mount *k* can slide backward and 30 forward in the sleeve *h h*, but with an intermediary or medial sleeve *j* which by its rotation gives a means of focusing the optical projection system. The sleeve *j* which is medial between the fixed tube *h* and the sliding 35 tube or mount *k*, is provided with helical slots driving the tube mount *k* in or out, one of these slots being shown on an enlarged 40 scale as *l*, Fig. 10, as engaging with a pin *m*, attached to the sliding mount *k*. The sleeve *j* is flanged and is actuated externally by 45 a finger lever or crank arm *o*, Fig. 7.

Sleeve *h* is fixed to panel *a* by cheese headed screws 12 which pass through slots 13 in the flange of sleeve *h* to accommodate 50 rotation of the sleeve *h* as and for the purpose hereinafter described.

Into the slidable tube or mount *k* a flanged disk *p* Fig. 8 is screwed disk-end first, this disk being apertured for the reception of the direct lens *e* and the correcting block *g* respectively. The flange of the direct lens is pinned to that face of the disk *p* with aspect away from the compound prism block *c*, and to the free end of the 60 flanged disk *p* is pinned a disk *q* herein-after called the main lens panel.

Upon that face of the main lens panel *q* most remote from the flanged disk *p* is mounted an adjustable sliding plate *r* Fig. 65 7 which is apertured for the reception of

the side lens *f* and fenestrated appropriately for the direct lens *e*, the flange of the side lens being pinned to that face of the slide plate *r* with aspect toward the reflecting prism *d*: provision for locking the sliding 70 plate *r* in the set position may conveniently take the form of set screws 14 traversing slots 15 in the panel *q* and screwing into the plate *r*, these slots being disposed as shown in Fig. 9 so as to function only when 75 adjusting for the separation of the axes of the lenses. Preferably cheese-headed set screws 14, Fig. 8 are screwed into the slide plate *r* from the back, holes being made in the disk *p* to admit a screw-driver. The 80 screws pass through slots in the panel *q* to accommodate the slight adjustment of the slide plate *r* which is required.

Over the disks *p* and *q* and the adjacent end of the sliding mount *k* is slid a barrel *s* 85 which is pinned, preferably in a removable manner, by internal radial lugs *t* to the disk or main lens panel *q* and forms the side wall of the dust tight containing chamber *u* for the compound prism block *c* and 90 its companion reflecting prism *d* by which the entering beam of light is divided between the direct lens *e* and the side lens *f*.

The prism system in front of the lenses, in the chosen example, the compound prism 95 block *c* with its companion reflection prism *d*, is combined as a unit with a removable part which co-acts with another part or other parts of the mounting of the optical system to form an accessible dust tight 100 chamber forward of the main lens panel and this removable part must be brought to one definite position by steady pins or like device so that disturbance of the adjusted and set position of the optical system in virtue of 105 removing and replacing the removable part is precluded.

As illustrated in Figs. 7 to 9 the compound prism block *c* with its companion reflection prism *d* is combined as a unit with a cap 110 plate *w* as by a clamping plate *x* and screw bolts *y*. The cap plate *w* and the plate *x* are appropriately fenestrated in the path of the entering beam of light and the cap plate *w* is pinned to the barrel *s*, being 115 brought to the hereinbefore cited definite register position by steady pins or the like device, for securing constancy of position.

Alternatively and where as illustrated in Figs. 13, the lenses are carried on and extend forwardly of a common panel 9, there may be an appropriately fenestrated box-like cap 10 carried from this panel 9 as on rods 11, this box-like cap 10 being suitably made removable from the panel and there 125 being provision such as by plates or velvet strips or both sliding over or on one another to complete the box-like cap as a dust tight chamber and at the same time allow of the requisite adjustment of the lenses. 130

Adverting once more to the construction illustrated by Figs. 7 to 12, the correcting block *g* behind the side lens *f* is brought to position and then held by a fenestrated 5 clamping plate *z* which is pinned to a flanged disk *1* which is screwed or fitted into the corresponding end of the sliding barrel *k* and fixed by a cross pin. The flanged disk *1* is appropriately fenestrated in the paths of 10 the direct beam and the reflected beam.

For operating iris diaphragms from outside the focusing mount so as to complete the taking system as a compact and reliable self-contained unit which is highly protected 15 against dust and damage, the expedient may be adopted of employing radial slotted pins *2* extending into the barrel *s* so as to engage pins *3* outstanding from the iris diaphragm levers into the path of the slots *2^a* of the 20 pins *2*. The pins *2* work in circumferential slots *2^b* provided in the barrel *s*, and carry dust proof cover-plates *4* working in slides *5*, clearance being left between the lens *f* and the inner end of the corresponding pin 25 *2* as shown in Fig. 7 to allow for the adjustment of the lens *f* from the lens *e*.

For the purpose of adjusting the separation of the lenses *e* and *f*, it is convenient to fit the barrel *s* with a pair of diametrically 30 opposite radial set screws *6*, *6* to co-act with the sliding plate *r* in obvious manner. When the correct separation is determined the adjustment is locked by binding the sliding plate *r* to the panel *g*, this being done by 35 tightening the screws *14* working through the slots *15* in the panel *g* to the plate *r*.

These screws *6*, *6* are then removed and their holes are then filled with dummy screws to prevent the locked setting being 40 tampered with.

To adjust the images as a group in the exact selected standard position to the course of the film, the fixed sleeve *h* of the mount is positively held against rotation in relation 45 to the front or panel *a* by means which can be externally influenced to rotate the sleeve

h, rotation being allowed by virtue of the pinning of the sleeve flange to the front or panel *a* being through the slots *13*. As figured, the flange of the sleeve *h* has a radial 50 finger *7*, Fig. 12, extending medially between lugs *8* outstanding from and fast with the panel *a* these lugs *8* having screw threaded holes fitted with opposing screws *9* by which the position of the finger and flange with 55 which it is integral can be adjusted. And when the required adjustment is made the flange of the sleeve *h* is locked to the front or panel *a* while to prevent tampering with the adjustment the opposing screws or finger or both may be removed.

Inasmuch as cameras of the kind described may be adapted to produce cinematograph films containing successive groups of separate color records wherein the separate color 65 record images are placed one above the other on a standard or single width film, either consecutively or spaced out with a color record or color records of another group or other groups intervening, or placed side by 70 side at the same level on a broad band, or at different levels on a broad band, it is to be understood that such variations are contemplated by and form part of the present invention and are included in the claiming 75 clauses hereof.

What we claim is:—

The process of standardizing cameras for taking a plurality of color value negatives concomitantly from the same point of view 80 which consists in taking a series of color value images, projecting the color value images through a standard projector so that they substantially superpose on a screen and then relatively adjusting the lens elements 85 of the camera so as to correct for lack of proper superposition of images as viewed on the screen.

In testimony whereof we affix our signatures.

FRANK TWYMAN.
HAROLD WORKMAN.
